TRUING TOOL FOR WATCH BALANCE
WHEELS

Walter Podgurski, Philadelphia, Pa.

Application September 3, 1936, Serial No. 99,224

6 Claims. (Cl. 33—203)

This invention relates to devices used by watchmakers for truing balance wheels and has as its main object the provision of means whereby the rim of a balance or like wheel may be accurately 5 adjusted to rotate concentrically upon its axis.

A further feature is in the provision of means whereby the pins, set in the rim of the wheel, may be calibrated with respect to their length and registration.

10 Another purpose is to produce a tool capable of minute adjustment in conformity with the proportions of the wheel undergoing operations.

These and other advantageous objects, such as compactness, convenience in operation and moderate cost, are accomplished by the novel construction, combination and arrangement of parts hereinafter described and illustrated in the accompanying drawing constituting an essential component of this disclosure, and in which:—

20 Figure 1 is a side elevational view of an embodiment of the invention, partially in section.

Figure 2 is a similar view of the opposite side.

Figure 3 is an edge view of the same.

25 Figure 4 is an enlarged sectional view taken on line 4—4 of Figure 1.

Figure 5 is a transverse sectional view taken on line 5—5 of Figure 4.

Referring to the drawing in greater detail, the device will be seen to consist of a tool having 30 duplicate jaws at each end.

The body of the tool is composed of two equal portions 15—16, substantially alike, in one of which, as 15, are firmly secured two spaced guide rods 17 arranged in parallel and slideable in corresponding openings 18 in the mating member.

Midway between the rods the elements 15—16 are formed concavely to provide space for a knurled circular head 20 from each side of which extend screws 21—22, threaded respectively right

40 and left hand into the elements 15—16 and by which the two sides of the implement may be forcibly moved towards or from each other.

Extending from the end portions of the elements 15—16 are jaws 23—24, inwardly bowed 45 at their outer ends, in which are fixed opposed, aligned terminals 25—26 having fine sockets in their proximate ends adapted to receive the pointed ends of wheel staffs reaching equally outward from the hub of the balance wheels to be trued.

50 It will now be obvious that by proper manipulation of the member 20, the wheels can be held rotatively between the jaws.

A bar 30, having a thickened lug 31 at one end, 55 is held slideable across the jaws 23—24 by clips

32—33 and is adjustable within them by a screw 34 threaded into the lug 31 and provided with a knurled operating head 35.

The inner end 36 of the screw is rotatable in an opening 37 in the jaw 23 and provided with a fixed collar 38. A set screw 39, in the jaw 23 provides means to clamp the screw when in its adjusted position. See Fig. 4.

A similar but larger set screw 40, in the jaw 24, 10 may be used to clamp the bar 30 against the clip 33. While clips 33 are permanently fixed, clips 32 and 41 can be opened or closed in latch fashion. Clips 32 and 41 may thus be turned on a pivot screw on one end of each clip and locked tight by a corresponding screw at the opposite end of each clip, thereby permitting a quick change of the bar 30 from one end of the tool to the other.

An elongated slot 46 in the bar 30 permits in connection with a clamping nut 47 longitudinal adjustment of a slide 50 transversely of the jaws. 20

In this slide 50 operates a screw 51 having an operating head 52 by which a sleeve 53 with an inside thread may be moved towards or from the plane of the balance wheel, this sleeve having fixed in its outer end a rod 54 turned angularly 25 at its end to constitute a feeler 55, the sleeve being flattened on one side to prevent turning, as shown at 56, Fig. 4.

From the foregoing it will be apparent that the feeler 55 may be moved longitudinally along 30 the bar 30, clamped to it by the screw 47 and then finely adjusted by the head 35 which moves the bar; also that the feeler may be finely adjusted, relative to the axis of the wheel being trued by the screw 52.

It is further apparent that the bar 30 and its appurtenances may be moved bodily to the other end of the instrument at will.

As many changes of construction could be made within the scope of the invention, it is to be 40 understood that all matter contained in the foregoing description or shown in the accompanying drawing shall be interpreted as illustrative and not in a limiting sense.

Having thus described the invention, what is 45 claimed as new and desired to secure by Letters Patent, is:—

1. In a balance wheel truing tool comprising two jaws adjustable toward and away from each other and provided with bearings for the ends of a wheel staff: a slotted bar, slidably mounted for movement independently of and across said jaws, a screw adjustment to minutely control said movement, clamping means to fixedly hold said bar in an adjusted position, a slide adapted for 50 55

- movement within the slot in said bar, a feeler adjustably mounted within said slide and adapted for movement at right angles to said slot, and means to fixedly hold the slide and the bar in place after adjustment in both directions.
5. 2. In a balance wheel truing tool comprising two jaws adjustable toward and away from each other and provided with bearings for the ends of a wheel staff: a slotted bar, slidably mounted for movement independently of and across said jaws, a screw adjustment to minutely control said movement, clamping means to fixedly hold said bar in an adjusted position, a slide adapted for movement within the slot in said bar, a feeler comprising a laterally bent tip and a straight shank, the latter being adjustably mounted within said slide and adapted for movement at right angles to said slot, and means to fixedly hold the slide and the bar in place after adjustment in both directions.
10. 3. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler adjustably mounted within said slide and adapted 15 for movement at right angles to said slot, and means to fixedly hold the slide and the bar in place after adjustment in both directions substantially as described.
15. 4. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler 20 comprising a laterally bent tip and a straight shank, the latter being adjustably mounted within said slide and adapted for movement at right angles to said slot, and means to fixedly hold the slide and the bar in place after adjustment in both directions substantially as described.
25. 5. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler 30 comprising a laterally bent tip and a straight shank, the latter being adjustably mounted within said slide and adapted for movement at right angles to said slot, and means to fixedly hold the slide and the bar in place after adjustment in both directions substantially as described.
35. 6. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler 40 comprising a laterally bent tip and a straight shank, the latter being adjustably mounted within said slide and adapted for movement at right angles to said slot, and means to fixedly hold the slide and the bar in place after adjustment in both directions substantially as described.

movement, clamping means to fixedly hold said bar in an adjusted position, a slide adapted for movement within the slot in said bar, a feeler comprising a laterally bent tip and a straight shank, the latter being adjustably mounted within said slide and adapted for movement at right angles to said slot, and means to fixedly hold the slide and the bar in place after adjustment in both directions.

5. 2. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler adjustably mounted within said slide and adapted 10 for movement at right angles to said slot, and means to fixedly hold the slide and the bar in place after adjustment in both directions substantially as described.

6. In a balance wheel truing tool comprising two jaws adjustable toward and away from each other and provided with bearings for the ends of a wheel staff: a slotted bar removably latched in position on said jaws and slidably mounted for movement independently of and across said jaws, a screw adjustment to minutely control said movement, clamping means to fixedly hold said bar in an adjusted position, a slide adapted for movement within the slot in said bar, a feeler comprising a laterally bent tip and a straight shank, the latter being adjustably mounted within said slide and adapted for movement at right angles to said slot, and means to fixedly hold the slide and the bar in place after adjustment in both directions substantially as described.

40. WALTER PODGURSKI.
